UNITED STATES PATENT OFFICE.

JOHN B. WELCH, OF SYRACUSE, NEW YORK.

DESIGN FOR A MOCCASIN.

No. 37,718.

Specification for Design.

Patented Dec. 5, 1905.

Application filed October 24, 1905. Serial No. 284,251. Term of patent 7 years.

To all whom it may concern:

Be it known that I, JOHN B. WELCH, a citizen of the United States, residing in the city of Syracuse, county of Onondaga, and State of New York, have invented a new, original, and ornamental Design for a Moccasin, of which the following is a specification, reference being had to the accompanying drawing, in which I show the moccasin in isometric perspective.

I claim—

The ornamental design for a moccasin, as shown.

JOHN B. WELCH.
